METHOD OF AND APPARATUS FOR CONTROLLING DREDGES

Application filed February 18, 1932. Serial No. 593,815.

This invention relates to improvements in methods of and apparatus for controlling dredges and its purpose is to provide an improved method and improved means for controlling the movements of the digging bucket of a dredge which is elevated by hoisting mechanism and moved through a cycle of operations during its excavating, elevating and dumping movements. The invention 10 may also be employed to advantage in connection with excavating and hoisting operations employed in other surroundings. This application is a continuation in part of my prior co-pending application Serial No. 15 546,652, filed June 24, 1931.

In the operation of a dredge, for example, the amount of energy expended and the work done at different stages of the cycle of operations of the digging bucket vary 20 throughout a wide range, depending upon the position of the bucket, the resistance encountered thereby and the presence or absence of a load in the bucket, and this makes it desirable to equip the hoisting apparatus 25 with devices for supplying the required amount of power at different stages of the digging and elevating operation and for counterbalancing or assisting the load represented by the bucket and its connected 30 parts during the return movement of the bucket from its dumping position to its digging position. The first stages of the operations may be called a work cycle because work must be expended during these stages 35 in excavating the material being operated upon and elevating it to the required height, and the subsequent stages during which the bucket is dumped and then returned to its excavating position may be termed a compression cycle because the forces exerted by 40 the bucket and its immediately connected parts are then opposed to the normal application of energy by the source of power by which the bucket is moved during the work 45 cycle. Efforts have heretofore been made to apply the required amount of energy in a different way during the different stages of the cycle of operations of the bucket and to control properly the dumping and return 50 movements of the bucket, by employing a

Diesel engine to drive a motor-generator set comprising a generator driven by the engine and supplying current to the motor which, in turn, has been connected to operate the hoisting drum, and a system of electrical controlling apparatus has been employed therewith so that the necessary energy has been applied during the different stages of the work cycle, and the energy derived from a bucket and its connected parts 55 during the compression cycle has been utilized for driving the motor as a generator and storing up energy through the reversal of the operations of the motor-generator set. While this form of apparatus has many advantages over the previously known forms 60 of apparatus for operating dredges and other hoisting devices, the apparatus is very costly and complicated and lacks the simplicity which should be present in apparatus 65 of this character.

The principal object of the present invention is to overcome the above mentioned difficulties by providing a new method and means for controlling the operation of 75 dredge mechanism, according to which the supply of energy for moving and controlling the load during the various stages of the work and compression cycles is furnished and controlled by the prime movers alone, 80 without necessarily employing any motor generator set or other auxiliary apparatus, so that the initial cost of the dredge equipment is greatly reduced and the speed and efficiency of operation greatly improved as 85 compared with previously known apparatus employed for dredge purposes. A further object of the invention is to provide controlling means for hoisting or dredging apparatus in which the movements of the digging 90 bucket or the like are effected and controlled by steam turbines which are connected with the hoisting mechanism in opposition to each other, so that one turbine supplies the power for moving the bucket through its 95 work cycle, and for braking the movement of the bucket during its dumping and downward movements, while the other turbine supplies the power for counterbalancing and controlling the movement of the bucket and 100

its connected parts during its return movement or compression cycle. An important feature of the invention is that one turbine is employed for accelerating the movement 5 of the bucket and the connected hoisting mechanism during the return movement of the empty bucket to digging position, while a braking action is exerted upon the bucket during the final stages of this return movement, either by the other oppositely connected turbine, which serves to elevate the loaded bucket, or by an automatically operated brake which is responsive to the speed of the return movement. Other objects of the 10 invention relate to various features of construction and arrangement of the apparatus and to various details of the improved method, which will appear more fully hereinafter.

20 The nature of the invention will be understood from the following specification taken with the accompanying drawings, in which one embodiment of the improved apparatus is illustrated. In the drawings,

25 Fig. 1 shows a somewhat diagrammatic side elevation of a dredge employed in excavating material from the bottom of a river or harbor and elevating it into a scow by which it is conveyed away, and illustrating 30 the positions of the paths of movement of the bucket at different stages of the work and compression cycles;

Fig. 2 is a chart or diagram illustrating the fluctuations in power required for the 35 movement of the bucket during different stages of the work and compression cycles for the duration of one complete cycle of operations of the bucket;

Fig. 3 represents, somewhat diagrammatically, a plan view of one form of hoisting mechanism adapted to be employed in 40 practicing the present invention;

Fig. 4 shows an enlarged top plan view of a portion of the hoisting mechanism shown 45 in Fig. 3 with a part thereof illustrated in horizontal section; and

Fig. 5 shows a side elevation of the friction brake which is embodied in the construction illustrated in Fig. 4 with the steam 50 cylinder and associated parts illustrated in vertical section.

As illustrated in Fig. 1, the dredge 10 comprises a hull 11 floated upon a body of water having its surface at 12. The normal 55 bed or bottom of the river or harbor in which the dredge 10 is operating is shown at 13, and the dredge is being operated to excavate this bed or bottom to produce a lower level, shown at 14. The bucket 15 of the dredge is 60 shown as being operated along the curved bank which connects the old bottom 13 with the new bottom 14 and this bucket or scoop is carried at the end of a hoisting beam or handle 16, the upper end of which passes 65 through a casing 17, known as a carriage,

which occupies a fixed position upon the inclined frame 18 projecting outwardly, in cantilever fashion, from one end of the hull 11. The outer end of this frame 18 is supported by wires or cables 19 which pass over a strut 20, fixed on the dredge, and are connected at their other ends to an intermediate part of the dredge, as shown at 21. The beam 16 is adapted to slide longitudinally in a guide in the carriage 17 to accommodate the movements of the bucket which are effected primarily by a cable 22 connected at its lower or outer end to the bucket and arranged to pass over a pulley 23 mounted on the outer end of the frame 18. After passing over this pulley, the cable 22 is directed downwardly and inwardly and passed around the hoisting drum 24 which is mounted on a suitable base within the hull 11. This drum is driven through intermediate mechanism from prime movers 25 which, in the present invention, take the form of two oppositely connected steam turbines, as heretofore indicated. The hull 11 is provided at its four corners with the usual posts or spuds 26 which are capable of being adjusted downwardly to the positions shown by dotted lines, wherein they rest upon the bottom 14 to support the hull against vertical movement during the operations of the bucket 15.

The beam or handle 16 may be raised and lowered to vary its effective length below the carriage 17 by means of an engine 28 which is mounted upon the frame 18 and which drives a pinion arranged to mesh with a rack bar 29 secured to the lower face of the beam or handle 16. In addition to the movement of the bucket 15 by the reciprocation of the beam or handle 16 through the carriage 17, the bucket 15 may be withdrawn toward the hull 11 by a cable 31 which is attached to the lower part of the beam and which extends through a set of fairlead sheaves or pulleys 32 mounted on the end of the hull, after which it is led rearwardly and passed around the drum or winch 33 mounted on the hull. The operations of the winch 33 and the engine 28 may be carried on in conjunction with the hoisting operations which are effected primarily by the cable 22 and the turbine-driven drum 24, in order to bring about the desired movements of the bucket 15.

In Fig. 1, the curve 35, drawn as a solid line, represents the path of movement of the bucket 15 during the excavating, elevating and dumping operations, while the curve 36, shown as a dotted line, represents the path of movement of the bucket during its return movement from its dumping position to its initial digging position. It will be apparent that the power which must be expended to move and support the bucket in different parts of its digging and dumping cycle, rep-

resented by the curve 35, may vary throughout a wide range and that the power which must be supplied to control or assist the movement of the bucket during its return cycle, may similarly vary throughout a wide range. These fluctuations in power have been plotted in the form of a curve 38 in Fig. 2, where the abscissæ represent intervals of time, and where the ordinates represent 5 sent units of power, such as horsepower, supplied to the bucket at different stages of its work and compression cycles. The various positions of the bucket during its work and compression cycles have been indicated by 10 letters *a*, *b*, *c*, *d* and *e* on the curves 35 and 36 in Fig. 1 and the corresponding positions of the bucket have been represented by the same letters on the curve 38 in Fig. 2.

As the bucket 15 moves from its lower 20 position *a* to the position *b* where its digging action is completed, the power which must be applied to move the bucket will normally tend to increase gradually because the bucket gradually assumes a more upright 25 path of movement and the power supply may fluctuate, depending upon the variations in resistance encountered by the bucket due to variations in the content of the material of which the bottom or bed of the river 30 or harbor is formed, so that the first part of the power curve 38 may have the form 38^a which represents the power supplied during successive intervals of time as the bucket moves from position *a* to position *b*. 35 As the bucket moves upwardly from position *b*, the power required tends to be less than that required during the last stages of the digging operation because the bucket is then partially supported by the buoyancy 40 of the water, but the required power increases as the bucket emerges from the water, because of the absence of this buoyancy, so that the power curve from position *b* to position *c* has a generally rising characteristic, 45 as shown at 38^b. The position *c* represents the high point in the movement of the bucket and it then has a downward movement to position *d*, this being the dumping operation of the bucket, and position *d* being 50 the final dumping position in which the bucket is located over the hopper of a scow 39 by which the excavated material is conveyed away. During this movement of the bucket, there is a rapid falling off of the 55 required power until it reaches a negative value, as shown by the portion 38^c of the curve in Fig. 2. That portion of the curve which lies below the zero line represents a stage in which work is being done by the 60 bucket and it is during this stage that power must be supplied to counteract or control the movement of the bucket as it moves downwardly. As the bucket reaches its final dumping position *d*, the power curve 65 has risen slightly above the zero line and,

then, upon beginning the return movement of the bucket to its digging position, it is necessary first to elevate the bucket from its position within the hopper of the scow 39 so that a positive application of power is required in moving the bucket from position *d* to position *e*, as shown by the portion 38^d 70 of the power curve 38. The bucket then begins to lower as it travels downwardly along the dotted curve 36 to its digging position *a* and during this movement the power curve 38 again descends rapidly and falls below the zero line, as shown at 38^e in Fig. 2. It will be noticed that the negative power required during the operation of restoring the bucket to its digging position is equal to or greater than the maximum power required during the work cycle of the bucket. 75 The operating mechanism for the bucket must therefore have at least as great a power capacity for application during the compression cycle as it has during the work cycle of the bucket.

The present invention fulfills the requirements of properly meeting the fluctuations in necessary power during the complete cycle of operations of the bucket, by reason of the embodiment in the operating apparatus of two oppositely connected steam turbines which may be alternately operated in a simple manner to provide the required actuation and control of the bucket during the various stages of its movement. In Fig. 3 of the drawings, there is illustrated somewhat diagrammatically a plan view of one form of bucket operating mechanism in which the drum 24 corresponds to the drum illustrated in Fig. 1 with two cables 22 wound around it for connection with the bucket 15. This drum is mounted on a shaft journaled in bearings 40 which are carried by the base or frame 41 adapted to be secured in fixed position within the hull of the dredge. The drum 24 is rotated by a gear 42 mounted on the same shaft as the drum and actuated by a pinion 43 fixed on a countershaft 44. The shaft 44 has secured thereon a herringbone gear 45 which meshes with a driving pinion 46 fixed upon the common shaft 47 of two steam turbines 25^a and 25^b which are mounted upon a part 90 of the base 41. These two turbines are supplied with steam through pipes 48 leading from a main supply pipe 49 and each of the pipes 48 has connected therein a valve or steam supply governor 50 for controlling the admission of steam to the adjacent turbine. These two valves or governors 50 are preferably interconnected as shown diagrammatically at 51 so that they may be controlled by a common lever to prevent the simultaneous admission of steam to both turbines while permitting either turbine to operate and supply power while the other turbine is idling. The turbine 25^a serves 95 100 105 110 115 120 125 130

as a prime mover for applying power to the drum from the initial digging position *a* to the position *c* where the hoisting of the bucket has been completed and the turbine 25^a is also utilized for operating the drum 24 during the elevation of the bucket from the dumping position *d* to the position *e* on the return movement, and it may also be employed for applying a braking effort to 10 the bucket at the limits of its dumping movement and of its downward return movement in order to bring the bucket to rest at its initial digging position. The other turbine 25^b acts as a prime mover during the lowering movements of the bucket, that is, during the dumping movement from the position *c* to the position *d*, and during the return movement from the position *e* to the initial position *a*, during which parts of the cycle, 20 this turbine 25^b serves to drive the dredge mechanism and accelerate it so that the bucket is free to move by gravity without having to drive any of the parts of the connected mechanism.

25 The controlling lever of the turbines may be shifted several times during the complete cycle of operations of the bucket in order to bring the proper turbine into operation to apply power during the different stages of 30 the cycle just referred to and also for the purpose of causing the hoisting turbine 25^a to retard the movement of the bucket at the ends of its dumping and return movements and, if desired, the braking action of the 35 turbine 25^a may be caused to take place automatically as hereinafter more fully explained. At the beginning of the digging operation, the controlling connections are set to start the turbines 25^a in operation in the 40 position *a* and this turbine continues to supply power, with the other turbine idling, until the bucket reaches the position *c*, whereupon the operator shifts the connection 45 51 so that the turbine 25^a then begins to idle while steam is admitted to the turbine 25^b so that the latter turbine applies 50 power and drives the drum 24 and the hoisting cables in the opposite direction in order to facilitate the dumping movement of the 55 bucket, due to its own weight, along the path *c*—*d*, thus relieving the bucket of any work in rotating the drum or operating other movable parts of the dredge mechanism. Before the bucket actually reaches the 60 position *d*, the connections 51 are again reversed so that the lowering turbine 25^b is cut off from the steam supply and steam is again admitted to the turbine 25^a so that the 65 latter turbine then acts as a brake to retard the bucket and bring it gradually to rest at the end of its dumping movement. This 70 turbine 25^a then continues to operate so that, after the contents of the bucket have been 75 dumped, the bucket is elevated by this tur-

bine along the path *d*—*e* at which point the connections are again changed so that the turbine 25^a begins to idle and power is applied through the turbine 25^b to drive the drum and the cable mechanism during the 70 lowering movement along the path *e*—*a*, thus assisting the normal motion of the bucket under the influence of gravity and speeding up the cycle during which no work is being done by the bucket. Before the 75 bucket reaches the position *a*, the connections are again changed to admit steam to the turbine 25^a and to shut off the supply of steam to the turbine 25^b, so that the turbine 25^a acts as a brake to retard the motion of the bucket as it approaches the initial digging position *a*. The connections 51 are 80 preferably such that there is a neutral zone between the two positions of the operating lever which effect the admission of steam to the two turbines so that when the lever is in its neutral position, neither turbine will operate. In the manner just described, the 85 application of energy to the drum 24 from the turbines 25^a and 25^b may be controlled 90 according to the method of the present invention to supply the required amount of power for moving and elevating the bucket during the work stages and for expediting 95 and retarding its movement at different stages of its movement where no work is being done in excavating or hoisting a load. Of course, the connections 51 may be shifted at other times during the operation, depending 100 upon the conditions which are encountered by the bucket during its movement.

105 Instead of depending entirely upon manual control for bringing the proper turbine into action at each different stage of the cycle of operations, automatic controlling mechanism may be employed and there is illustrated in the drawings, one form of automatic controlling mechanism which may be used to effect the braking or retardation 110 of the movement of the bucket at the ends of its dumping and return movements, either by actuating a friction brake or by admitting steam to the turbine 25^a which supplies the power for moving the bucket in the opposite direction. This mechanism comprises 115 a governor 55 mounted upon the shaft 44 to rotate therewith. This governor includes a casing 56 having a cover 57 provided with a central aperture 57^a through which extends 120 the governor shaft 58. This shaft has a disk 59 secured on the inner end thereof within the casing 56 and provided with an annular groove which is engaged by the inwardly extending arms of two bell crank 125 levers 60 each of which is pivoted on a bracket 61 carried by the casing cover 57. The other arms of these two bell crank levers are provided with weights 60^a at their 130 ends and these weights are connected by a

- coil spring 62 which tends to prevent their separation under the influence of centrifugal force. When the speed becomes great enough to cause the centrifugal force acting 5 on the weights 60^a to separate, the bell crank levers are thereby actuated to shift the governor shaft 58 inwardly and thus actuate the valve 64 which is adapted to control the admission of steam to a brake 10 controlling device or to the turbine 25^a. The valve 64 comprises a casing 65 having mounted therein a piston 66 which is secured on the shaft 58. The piston 66 is provided with an annular groove 66^a which, when the 15 piston is in the proper position, is adapted to establish communication through the cylinder from the steam supply pipe 67 to the steam outlet pipe 68. The outlet pipe 68 has two branches 68^a and 68^b which are 20 connected thereto by a T-connection 69 and these branches are controlled by separate manually operated valves 70 and 71, respectively, so that either branch pipe may be closed when desired.
- 25 The branch pipe 68^a leads to a steam ram 72 which is secured on the base 41 and which comprises a cylinder 73 having mounted therein a piston 74 adapted to be moved within the cylinder by the steam which is 30 admitted thereto. The piston 74 is connected to a piston rod 75 which leads through a packing gland 76 in the end wall of the cylinder and is pivotally connected to a link 77. The other end of this link is 35 pivoted on one arm of a bell crank lever 78 which is pivotally supported at 79 on a bracket 80 secured on the base 41. The other arm of this bell crank lever 78 is connected to one end of a brake strap 81 which 40 extends around the peripheral surface of a brake drum 82 secured on the shaft 44 with its other end attached to the brake 80 at 83. When the piston 74 of the arm is operated by steam pressure, the bell crank lever 78 is 45 actuated to tighten the brake strap around the drum 82 and thus arrest the rotation of the connected drum 24 and the bucket 15 connected thereto. Suitable means, such as a spring 84, located in the cylinder 72, may 50 be employed for effecting reverse movement of the piston 74 and thereby releasing the grip of the brake strap 81 on the drum 82 at the end of the operation which will ordinarily be determined by the cessation of 55 speed and the consequent closing of the valve 64 by the centrifugal governor 55. If desired, any other suitable form of governor might be employed for this purpose.
- Instead of retarding the movement of the 60 bucket by means of the brake 81-82, the valve 70 may be closed and the valve 71 opened so that when the governor-controlled valve 64 is opened, the steam admitted thereto will pass through the other branch pipe 68^b to the turbine 24^a, thus tending to ro-
- tate this turbine in a direction which is counter to the motion of the drum 24 and bucket 15 at that time. In this way, the turbine 25^a may be automatically brought into operation to retard the motion of the 70 bucket at the end of its dumping movement and also at the end of its return movement to the initial digging position. With or without this automatic controlling feature, 75 it will be apparent that the present invention provides a simple means of controlling the application of power to the bucket and that this means and method of operation eliminate the necessity for using the expensive and complicated electrical apparatus 80 which has heretofore been employed, while at the same time obtaining the advantage of greater speed and economy of operation. The present invention may be applied to dredges or hoists of various capacities but 85 it is particularly effective when employed in connection with dredges or hoists where great tension is set up in the cables as a result of the heavy loads being excavated or hoisted, for example, dredges in which the 90 load carried by each hoisting cable may be from 100 to 200 tons. Although the invention has been illustrated as comprising two separately constructed turbines, it will be understood that two turbines may be combined in one structure for permitting the application of power in opposite directions 95 within the concept of the present invention.
- Although one form of the improved apparatus has been shown and described in 100 connection with the explanation of one example of the improved method of dredge control, it will be understood that the invention may take various forms coming within the scope of the appended claims.
- I claim:
1. The combination with a dredge, of hoisting mechanism mounted on said dredge, and a pair of oppositely connected steam turbines connected to said hoisting mechanism for controlling the opposite movements thereof.
  2. The combination with a dredge, of hoisting mechanism mounted on said dredge, 110 a bucket operated by said hoisting mechanism, and a pair of oppositely connected steam turbines having a common connection with said hoisting mechanism for controlling the opposite movements of said bucket.
  3. The combination with a dredge, of hoisting mechanism mounted on the dredge, 115 a bucket operated by said hoisting mechanism, and controlling mechanism for said bucket comprising a pair of oppositely connected steam turbines having connections whereby they may be employed alternately for effecting positive movement of said bucket and for braking the downward movements of said bucket.
  4. The combination with a dredge, of 120

hoisting mechanism mounted on the dredge, a bucket operated by said hoisting mechanism, a pair of oppositely connected steam turbines having connections whereby one

- 5 turbine may be employed for operating said hoisting mechanism to move said bucket in one direction and the other turbine may be employed for accelerating the movement of the bucket in the opposite direction, and
 10 means for automatically bringing said first named turbine into operation for retarding the movement of said bucket in said last named direction.

5. The combination with a dredge, of
 15 hoisting mechanism mounted on the dredge, a bucket operated by said hoisting mechanism, a pair of oppositely connected steam turbines having connections whereby one turbine may be employed for operating said
 20 hoisting mechanism to move said bucket in one direction and the other turbine may be employed for accelerating the movement of the bucket in the opposite direction, and means including an automatic governor re-
 25 sponsive to the speed of movement of the bucket for admitting steam to said first-named turbine to apply power for retarding the movement of said bucket in said last named direction.

30 6. The combination with a dredge, of hoisting mechanism mounted on the dredge, a bucket operated by said hoisting mechanism, a pair of oppositely connected steam turbines having connections whereby one
 35 turbine may be employed for operating said hoisting mechanism to move said bucket in one direction and the other turbine may be employed for accelerating the movement of the bucket in the opposite direction, and a
 40 brake for retarding the final movement of said bucket in said last named direction.

7. The combination with a dredge, of hoisting mechanism mounted on the dredge, a bucket operated by said hoisting mechanism, a pair of oppositely connected steam turbines having connections whereby one turbine may be employed for operating said hoisting mechanism to move said bucket in one direction and the other turbine may be
 45 employed for accelerating the movement of the bucket in the opposite direction, a brake for retarding the final movement of said bucket in said last named direction, and automatic means responsive to the speed of
 50 movement of said bucket for actuating said brake to retard the final movement of said bucket in said last named direction.

8. The method of controlling the operation of the digging bucket of a dredge, having elevating and downward movement, by oppositely connected steam turbines, which consists in employing one turbine to effect positive movement of the bucket during its elevating movements and to brake
 60 the movement of the bucket during its

downward movements and employing the other turbine to control the speed of movement of said bucket during its downward movements.

9. The method of controlling the operation of a digging bucket of a dredge by oppositely connected steam turbines which consists in employing one turbine to move the bucket through the digging and elevating portions of its cycle, employing the other turbine operating in a reverse direction to control the movement of the bucket during the latter portion of its dumping movement, then employing said first named turbine to control the movement of the bucket during the elevating portion of its return movement, and finally employing said second named turbine to control the movement of the bucket during the final downwardly directed portion of its return move-
